ANKLE MARKER STRAP FOR ANIMALS

Cuthbert Brierley, Nettlebed, England, assignor to Dalton Supplies Limited, Nettlebed, England, a British company

Filed Oct. 21, 1966, Ser. No. 4,368

Claims priority, application Great Britain Sept. 22, 1966

Term of patent 14 years

Int. Cl. D30—99

U.S. Cl. D30—43

FIG. 1.

FIG. 2.

FIG. 3.

FIG. 4.

FIG. 5.

The essential features of the design reside in the full line portions of the drawings.

I claim:

The ornamental design for an ankle marker strap for animals, substantially as shown and described.
